United States Patent Office

Des. 186,376
Patented Oct. 20, 1959

186,376

BRASSIERE

Theo B. Schaumer, Los Angeles, Calif., assignor to Munsingwear, Inc., Minneapolis, Minn., a corporation of Delaware

Application December 19, 1958, Serial No. 53,841

Term of patent 14 years

(Cl. D20—4)

FIG. 1.

FIG. 2.

I claim:

The ornamental design for a brassiere, substantially as shown.
